UNITED STATES PATENT OFFICE

DONALD H. REEVES, OF DAYTON, OHIO, ASSIGNOR TO FRIGIDAIRE CORPORATION, OF DAYTON, OHIO, A CORPORATION OF DELAWARE

DESIGN FOR A DRINKING WATER COOLER FOUNTAIN

Application filed November 24, 1930. Serial No. 37,776. Term of patent 7 years.

To all whom it may concern:

Be it known that I, DONALD H. REEVES, a citizen of the United States of America, residing at Dayton, county of Montgomery, State of Ohio, have invented a new, original, and ornamental Design for Drinking Water Cooler Fountains, of which the following is a specification, reference being had to the accompanying drawing, forming part thereof.

The figure is a view in perspective of a drinking water cooler fountain showing my new design. The shading is intended to in-

dicate the play of light on the surface and does not designate any pattern on the drinking water cooler fountain. The opposite side, not shown on the drawing, is substantially the same as the side shown.

I claim:

The ornamental design for a drinking water cooler fountain as herein shown and described.

In testimony whereof I hereto affix my signature.

DONALD H. REEVES.
